(57) **CLAIM**

I claim the ornamental design for the collapsible dish drainer, as shown and described.

DESCRIPTION

FIG. 1 is a perspective view of the collapsible dish drainer, showing my new design;

FIG. 2 is a front view of the collapsible dish drainer, the back view being a mirror image;

FIG. 3 is a top view of the collapsible dish drainer;

FIG. 4 is a left side view of the collapsible dish drainer, the right side view being identical;

FIG. 5 is a bottom view of the collapsible dish drainer; and,

FIG. 6 is a perspective view of the collapsible dish drainer, shown with the collapsible dish drainer in a collapsed position.
